(57) **CLAIM**

An ornamental design for a two piece jaw type clip, as shown and described.

DESCRIPTION

FIG. 1 is a perspective view of our two piece jaw type clip; FIG. 2 is a top plan view thereof;

FIG. 3 is a rear view thereof;

FIG. 4 is a right side view, the left side being a mirror image thereof;

FIG. 5 is a bottom view thereof; and,

FIG. 6 is a front view thereof.

A magnet is shown in dotted line for illustrative purposes and forms no part of the present design.
